UNITED STATES PATENT OFFICE.

REUBEN H. HELSEL, OF LONG ISLAND CITY, NEW YORK, ASSIGNOR, BY MESNE ASSIGNMENTS, TO THE AUTOMATIC TICKET SELLING AND CASH REGISTER COMPANY, OF NEW YORK, N. Y., A CORPORATION.

TICKET-ISSUING MECHANISM.

1,304,976.

Specification of Letters Patent. Patented May 27, 1919.

Original application filed June 8, 1917, Serial No. 173,474. Divided and this application filed January 12, 1918. Serial No. 211,540.

To all whom it may concern:

Be it known that I, REUBEN H. HELSEL, a citizen of the United States, and a resident of Long Island City, Queens county, New York, have invented certain new and useful Improvements in Ticket-Issuing Mechanisms, of which the following is a specification.

The present invention relates to improvements in ticket issuing mechanisms adapted to issue one or a plurality of tickets, proportionate to the length of the operating movement transmitted thereto. My improved mechanism is designed to be simple in construction and to operate on a new principle which renders it particularly efficient and positive in its action to effect the proper delivery of the tickets.

The present application is a division of my application relating to improvements in coin controlled ticket machines, Serial No. 173,474 filed June 8, 1917.

My invention consists in the improved ticket issuing mechanism and in the various subcombinations, separate purpose mechanisms, elements, and parts thereof illustrated in the accompanying drawings and herein-after described at length and particularly claimed, and in such variations and modifications thereof as will be obvious to those skilled in the art to which my invention relates.

In the drawings accompanying and forming a part of this specification and wherein the preferred embodiment of my invention is illustrated, and wherein the same reference numerals are used to designate the same parts in the various views:

Figure 1 is a plan view illustrating a desirable embodiment of my invention.

Fig. 2 is a fragmentary view illustrating the various features of my improved mechanism in side elevation.

Fig. 3 is a similar view showing the parts in different position.

Referring to the drawings, the reference numerals 10, 11 designate supporting plates or frames spaced apart from one another and of such size, form and construction as to support the various elements of my mechanism hereinafter referred to at length in

proper position relative to one another, so that they may coöperate in the manner specified.

The reference numeral 12 designates the main driving shaft of my machine wherefrom the various elements thereof are operated. As is readily understood, this driving shaft may be rotated to actuate the ticket issuing mechanism, now to be described, by any desirable means, as for instance, the coin controlled operating means described in my application, Serial No. 173,474 aforesaid. As therein provided for the operating movement imparted to the shaft 12 is proportionate to the value of the coin employed so as to deliver one or a plurality of tickets.

The construction and operation of the ticket issuing mechanism of my present invention is as follows. Secured to the main drive shaft 12 of the machine is a crank 66 located preferably beyond the plate 11, as shown in Fig. 1, and 67 is an oscillating strip feeding shaft supported in bearings in the plates 10, 11 and having an arm 68 with which the crank 66 is operatively connected through a link 69, whereby as the shaft 12 rotates oscillating motion is communicated to the said last mentioned shaft. Secured to the shaft 67 and located between the plates 10 and 11 is a supporting member 70 to which a reciprocating strip feeding member 71 is pivotally secured at 72; and said feeding member is provided with a pin 73 with which inclined surfaces 74, 75 at the free end of a spring actuated holding member 76 engage, the said last mentioned member being pivotally connected at 77 with an arm 78 carried by the supporting member 70, and 79 being a spring which acts to draw the holding member inward and toward the shaft 67.

The reference numeral 80 designates a curved guide plate secured to the plate 11, and 81 a pin carried by the strip feeding member 71 and adapted to move along the upper surface of said guide when said member is moved to the left, Figs. 1 and 3, and along the under surface of said guide when said member is moved to the right and returned to its initial position. A curved strip supporting plate and guide 82 having a slot

- 83 in which the cylindrical end 84 of the strip feeding member 71 operates is secured in place between the plates 10, 11, and over which a ticket strip provided with holes at 5 suitable intervals into which the round end of the feeding member may enter, passes, the ticket strip being held against the plate 82 by means of a spring pressed holding member 85.
- 10 The strip feeding mechanism above described operates as follows: Referring to Figs. 1 and 3, the various elements of the strip feeding mechanism are illustrated in Fig. 2 in the positions which they occupy 15 when the machine is at rest, at which time the extremity of the round end 84 is below the surface of the plate 82 and out of engagement with the ticket strip, and the pin 81 lies adjacent the right hand end of the guide 20; while Fig. 3 shows the position of the parts just after the machine has commenced to operate, the round end 84 having been moved into a hole in the ticket strip and the movement of the strip feeding member 71 25 to the left having just commenced.
- The elements through which the ticket issuing mechanism is operated are so arranged and proportioned that initial movement of the oscillating shaft 67 will move 30 the strip feeding member 71 bodily upward and in a direction substantially parallel with its longitudinal axis, and project the end 84 thereof through a hole in the ticket strip, after which and upon further angular 35 movement of the said shaft the pin 81 will slide along the upper side of the guide 80. During this forward movement the strip feeding member will lag somewhat relative to the holding member 76, and the pin 73 40 thereof will move along the inclined surface 74 of the holding member 76 in opposition to the spring 79. At the end of the movement of the feeding member to the left the pin 81 will run off the guide 80 and, as 45 the said feeding member begins its return movement, the free end thereof will be withdrawn from the hole in the ticket strip and the pin 81 will slide along the under side of the guide 80 during the return movement 50 thereof, during which movement the feeding member will again lag somewhat and the pin 73 thereof will move along the inclined surface 75 of the member 76 in opposition to the spring 79 until the pin 81 55 runs off the guide 80 at the end of the return movement of the parts; all as will be understood from the full and dotted lines in Fig. 3 of the drawings; the purpose of the holding member 76, the spring 79, the inclined surfaces 74 and 75, and the pin 73 being to keep the pin 81 in contact with the guide 80 during the forward and return movements of the strip feeding mechanism, and the feeding member in engagement with 60 the ticket strip upon the forward movement,

and out of engagement therewith upon the return movement of said member, as will be appreciated.

At 47 is shown a knife operating cam carried by the driving shaft 12 arranged to 70 engage a roller 48 carried by a knife operating lever 49, the latter being pivotally supported from the plate 10 at 50 and the said lever being drawn toward the cam 47 by a spring 51 as best shown in Fig. 3 of the 75 drawing. The free end of said lever is operatively connected with a knife 86 pivotally supported at 87 through a link 88, and said knife acts to sever a ticket from the ticket strip each time it moves upwardly; and the 80 strip feeding mechanism and the knife being each operated once at each rotation of the shaft 12, it follows that each rotation of said shaft will advance the strip a length corresponding with a single ticket, after 85 which a ticket will be cut off from the strip; the number of rotations of the shaft and the number of tickets cut off from the strip and issued to the purchaser each time the machine is set into operation being dependent upon the operating movement imparted thereto.

Having thus described my invention and what I claim as new and desire to secure by Letters Patent is:

1. Ticket strip feeding mechanism comprising an oscillating shaft, a supporting member carried by and extending from said oscillating shaft, a reciprocating strip feeding member one end of which is pivotally 100 connected with said supporting member adjacent the free end thereof and the free end of which member is adapted to engage and feed a ticket strip, and which strip feeding member extends substantially at right angles to said supporting member and is movable bodily in the direction of its length to cause its free end to engage the ticket strip aforesaid, means for maintaining the free end of said strip feeding member in engagement with a ticket strip during its forward feeding movement, and out of engagement with the strip during its return movement, a curved ticket strip supporting plate located adjacent the path of movement of the free end of said ticket strip feeding member, and extending transverse to the longitudinal axis thereof, and means for operating said oscillating shaft.

2. Ticket strip feeding mechanism comprising an oscillating shaft, a reciprocating strip feeding member movable bodily in the direction of its length and one end of which is pivotally connected with said oscillating shaft to one side of the axis thereof through 125 a supporting member carried by said shaft, and the free end of which strip feeding member is adapted to engage and feed a ticket strip, means for maintaining the free end of said strip feeding member in engage- 130

- ment with a ticket strip during its forward feeding movement, and out of engagement with the strip during its return movement, a curved ticket strip supporting plate located adjacent the path of movement of the free end of said ticket strip feeding member and extending transverse to the longitudinal axis thereof, and means for operating said oscillatory shaft.
- 10 3. Ticket strip feeding mechanism comprising an oscillating shaft, a reciprocating strip feeding member one end of which is pivotally connected with said oscillating shaft to one side of the axis thereof through a supporting member carried by said shaft, and the free end of which strip feeding member is adapted to engage and feed a ticket strip, a spring operated holding member carried by said oscillating shaft and which 15 member is operatively connected with said strip feeding member, means for maintaining the free end of said strip feeding member in engagement with a ticket strip during its forward feeding movement, and out of engagement with the strip during its return movement, a curved ticket strip supporting plate located adjacent the path of movement of the free end of said ticket strip feeding member, and means for operating said oscillating shaft.
- 20 4. A ticket strip feeding mechanism comprising an oscillating shaft, a supporting member carried by said shaft, a reciprocating strip feeding member pivotally connected with said supporting member and the free end of which is adapted to engage the strip, a pin carried by said feeding member, a guide member along the upper and lower surfaces of which said pin moves during the forward and return movements of said feeding member, a spring actuated holding member carried by said supporting member and having two inclined surfaces and a second pin carried by said feeding member and with which said inclined surfaces engage, one during the forward and the other during the return movement of said feeding member.
- 25 5. A ticket strip feeding mechanism comprising an oscillating shaft, a supporting member carried by said shaft, a reciprocating strip feeding member pivotally connected with said supporting member and the free end of which is adapted to engage the strip, a pin carried by said feeding member, a guide member along the upper and lower surfaces of which said pin moves during the forward and return movements of said feeding member, a spring actuated holding member pivotally connected with said supporting member and having two inclined surfaces, and a second pin carried by said feeding member and with which said inclined surfaces engage, one during the forward and the other during the return movement of said feeding member.
- 30 6. A ticket strip feeding mechanism comprising an oscillating shaft, a supporting member carried by said shaft, a reciprocating strip feeding member pivotally connected with said supporting member and the free end of which is adapted to engage the strip, a pin carried by said feeding member, a guide member along the upper and lower surfaces of which said pin moves during the forward and return movements of said feeding member, a spring actuated holding member pivotally connected with said supporting member and having two inclined surfaces, and a second pin carried by said feeding member and with which said inclined surfaces engage, one during the forward and the other during the return movement of said feeding member.

In witness whereof I have hereunto set my hand at the city, county and State of New York, this 22nd day of December, 1917.

REUBEN H. HELSEL.
